United States Patent Office.

WILLIAM HALL, OF GEORGETOWN, ILLINOIS.

Letters Patent No. 77,976, dated May 19, 1868.

IMPROVED SANDALS.

The Schedule referred to in these Letters Patent and making part of the same.

TO ALL WHOM IT MAY CONCERN:

Be it known that I, WILLIAM HALL, of E. and I., of Georgetown, in the county of Vermillion, and State of Illinois, have invented a new invention, to be affixed to the bottom of sandals or other wear for the feet, which I call "Spurred Sandals."

The sandals may be made after the common form, a sole, a spur-piece around the heel, straps and rings for fastening on the foot, for travelling on ice, sleet, or roofing.

And, to enable others skilled in the art to make and use my invention, I will proceed to describe its construction and operation; and I do declare the following is a full and exact description of it, reference being had to the drawings and figures accompanying this description.

For a sandal of the eighth size, I make one bar, seven and a half inches long, with a blunt spur at each end, one-half or three-fourths of an inch long, (more or less,) one-fourth of an inch square, turned at right angles with the bar, gradually flattening from each end to the middle, and that to be one-third the thickness of this bar. Second bar of the same iron as the other, one-fourth of an inch, with a spur, as before, and four and a half inches long, flattened from the spur to the flat end; that end made round, and punched or drilled one-fourth of an inch from the end, to receive the spur of the long bar. The third bar, a half moon, of same bar of iron as the other, with a spur at each point, and gradually flattened from each point to the middle of bar or half moon, this bar or half moon to be of size and width between the spurs to reach across the heel. A wedge is made for the hollow of the foot, of sufficient side-width and thickness to fill up the hollow of the foot, from the heel to the ball, fastened, by two small nails through wedge and sole, and which can be removed for straight wear.

The bars are to be fastened to the sandals as follows: End bar 1 is to be fastened at the left side of the heel, and extend, across the foot, to the right side of the ball, fastened firmly with wire through the sole, and twisted or clinched. The other bar, 1, is fastened at the right side of heel; extends across foot to left side of ball; the four-and-a-half-inch bar 2, flat end, to be placed on the spur of bar 1, at ball of foot, across to the toe; second bar, 2, to be placed on the spur of bar 1, and extend across to toe, as represented, all firmly wired at each end and crossing.

All the bars can be placed on the upper side of the sandal, wired and fixed as on the bottom, the spurs perforating the bottom or sole.

What I claim as my invention is—

The bars, spurred and affixed to the bottoms of the sandals or other covering for the feet.
